(57) **CLAIM**

The ornamental design for a side rail for electric vehicle, as shown and described.

DESCRIPTION

FIG. 1 is a perspective view of a side rail for electric vehicle, according to a first embodiment;

FIG. 2 is a front view thereof;

FIG. 3 is an enlarged left side view thereof;

FIG. 4 is an enlarged right side view thereof;

FIG. 5 is a top view thereof;

FIG. 6 is a bottom view thereof;

FIG. 7 is another view of FIG. 2, showing an illustration of use on an electric vehicle;

FIG. 8 is a perspective view of a side rail for electric vehicle, according to a second embodiment;

FIG. 9 is a front view thereof;

FIG. 10 is an enlarged left side view thereof;

FIG. 11 is an enlarged right side view thereof;

FIG. 12 is a top view thereof;

FIG. 13 is a bottom view thereof; and,

FIG. 14 is another view of FIG. 9, showing an illustration of use on an electric vehicle.

The broken lines shown in the drawings illustrate environment and portions of the side rail for electric vehicle that form no part of the claimed design.

The rear of the side rail for electric vehicle is not part of the claimed design, and so the rear view has been omitted.
